UNITED STATES PATENT OFFICE.

ALFRED L. EUSTICE, OF CHICAGO, ILLINOIS.

FUSE.

1,411,332.

Specification of Letters Patent. Patented Apr. 4, 1922.

Application filed September 3, 1918. Serial No. 252,334.

To all whom it may concern:

Be it known that I, ALFRED L. EUSTICE, a citizen of the United States, residing at Chicago, in the county of Cook and State of Illinois, have invented certain new and useful Improvements in Fuses, of which the following is a specification.

This invention relates to fuses, and particularly to the removable cartridge type of fuse.

The object of this invention is to simplify and improve the construction of the cartridge type of fuse, whereby the parts thereof cooperate in a novel and efficient manner to meet the various requirements for successful commercial use.

This and other objects are accomplished by means of the construction disclosed by the accompanying sheet of drawings, in which—

20 Figure 1 is a side elevation, parts being in section, of my improved fuse,

Figure 2 is a detail side elevation of one of the two knife blade contact terminal members disclosed in Figure 1,

25 Figure 3 is a detail perspective view of a collar which is fitted over the narrow neck portion of the knife blade terminal,

Figure 4 is a detail perspective view of an associated member also mounted over the narrow neck portion of the knife blade terminal,

30 Figure 5 is a side elevation of the knife blade terminal with the parts shown in Figures 3 and 4 applied thereto,

35 Figure 6 is a longitudinal sectional view, and Figure 7 an end elevation of the threaded member which is fitted into each end of the shell,

Figure 8 is an end elevation, and Figure 9 40 a side elevation of a disc for preventing rotation of the knife blade contact terminal and associated members mounted thereon,

Figure 10 is an end elevation of the fuse, and

45 Figure 11 is a sectional view taken in the plane of line 11—11 of Figure 1.

The various novel features of my invention will be apparent from the following description and drawings, and will be particularly pointed out in the appended claims.

Referring to the drawings, it will be noted that I have provided a shell 15 formed of some suitable insulating material, such as fibre, in each end of which is fitted a ferrule 16, the smaller externally threaded portion

55 17 of which is screwed into the end of the

shell 15. The larger externally threaded portion 18 of the ferrule 16 projects beyond the edge of the shell and receives a threaded cap 19 to be referred to later. The ferrule 16 is formed to provide upon the shell, at its outer end, a cylindrical end opening. This is defined in the illustrative embodiment by an inwardly extending circular flange 20, and this flange is provided with oppositely arranged notches 21, so that the shell may be said to have a notched cylindrical end opening. A knife blade terminal 22, at each end of the fuse, is provided with a reduced neck portion 23 having therein a hole 24 for the reception of a bolt or other means by which a fuse link 25 can be secured thereto. Surrounding the neck 23 of each knife blade terminal member 22 is a washer 26 having a rectangular opening 27 through which it fits 70 the neck, and a cylindrical periphery through means of which it fits the cylindrical end opening of the shell. This washer 26 abuts shoulders 28 formed on the knife blade contact 22. Also mounted over the narrow neck 80 portion 23 of the contact terminal is a member 29 also having a rectangular opening fitting the neck 23, and provided with oppositely arranged lugs or shoulders 31, adapted to pass through the notches of the end 85 opening. The members 26 and 29 may be formed integrally with each other. They are secured against longitudinal displacement upon the neck of the knife blade 22, as, for instance, by striking up fillets of metal 90 at 31, as shown in Figure 5 of the drawings. The washer 26 and lug bearing member 29 thus constitute a shouldered collar on the terminal, and provide it with a cylindrical portion having a circumferentially restricted 95 shoulder or shoulders.

In assembling the contact terminal, the inner end is passed through the circular opening formed by the circular flange 20 of the member 16, the projections or shoulders 100 31 passing through the notches 21 in said circular flange. When the projections 31 have passed into the notches 21 sufficiently to permit a turning movement of the knife blade contact, the latter is turned, whereby 105 the knife blade contact is locked against longitudinal movement by the shoulders 28 and 31 engaging opposite walls of the circular flange 20, it being understood that the portion 26 is of substantially the same 110 width as the width of the circular flange 20.

To prevent rotation normally of the knife

blade contact 22, and the associated baffle washer mounted thereon, a disc 32 is provided, said disc having a central opening 33 for the reception of the knife blade contact, 5 the opening 33 preferably being just large enough to accommodate the knife blade contact. The under side of the disc 32 is provided with a plurality of diametrically arranged projections 34 which pass into the 10 notches 21 in the circular flange 20, thereby locking the knife blade against rotation. An end cap 19 is provided for each end of the shell, said end cap having an integrally threaded portion for cooperating with the 15 threaded portion 18 of the member 16, the end cap in each case being screwed inwardly to the extent that its inwardly extending flange 35 presses against the outer side of the disc 32 for locking all of the parts in 20 their normal positions.

Since the disk 32 extends outwardly to receive the end cap, it will overlie and seal the joint between the cylindrical bearing faces of the terminal and end opening.

25 It will be appreciated that if desired only one notch 21 may be provided in the flange 20, and only one projection 34 be provided on the disc 32, or any other number of notches and projections may be provided. 30 The disc 32 also prevents an endwise discharge of gases which may be formed by blowing of the fuse, the gases being directed radially outwardly through grooves 36, registering with the notches 21, the 35 grooves 36 leading to the threaded portion 18 along which gases may escape.

From the foregoing it will be seen that the end flanges on the shell, with which the terminals 22 interlock, may remain permanently with the shell in the disassembly of the terminals; that notwithstanding assembly of the pair of terminals and the connecting fusible link outside the shell, they can be assembled with the fixed end flanges 45 on the shell by passing them endwise through these flanges and through the shell while the blades are in the longitudinal plane of the notches of said flanges, and until disks 26 coincide with the flanges, and 50 then interlocked against longitudinal displacement by a partial rotation of the blades; that in this turning movement, and during use, said disk 26 provides a cylindrical bearing for the terminal within the 55 flanges, and so centers and stabilizes the terminal; that the terminals are locked against rotation back to the releasing point by means of locking disks 32, which have definite seating positions upon the flanges, 60 and so insure alinement of the terminal blades in one and the same axial plane; also that the caps which hold the locking disks in assembly are free to rotate for screwing to and from position, and are threaded upon 65 the same integral parts that carry the

flanges; and, finally, that in the assembly the joints between the parts are effectively closed against escape of gas except through the notches 21, ducts 36, and screw threads 18, which provide a long controlled passage-way that relieves the gases of any harmful effects. 70

It is my intention to cover all modifications of my invention falling within the spirit and scope of the following claims. 75

What I claim is:

1. In a fuse, a shell provided with a cylindrical end opening having a notch in the cylindrical wall thereof, a terminal member constructed with a cylindrical portion fitting the cylindrical end opening and having a circumferentially restricted shoulder adapted to pass through the notch and to a position for interlocking the terminal and shell longitudinally, a disk fitting a portion of the terminal to prevent relative rotation between the disk and terminal, and an end cap clamping the disk upon the shell. 80 85

2. In a fuse, a shell provided with a cylindrical end opening having a notch in the cylindrical wall thereof, a terminal member constructed with a cylindrical portion fitting the cylindrical end opening and having a circumferentially restricted shoulder adapted to pass through the notch and to a position for interlocking the terminal and shell longitudinally, a disk fitting a portion of the terminal to prevent relative rotation between the disk and terminal and adapted to interlock with the shell to resist rotation thereon, and an end cap securing the disk upon the shell; said disk overlying the joint between the cylindrical surfaces of the terminal and the end opening. 90 95 100

3. In a fuse, the combination of a shell having a cylindrical end opening, a knife blade terminal having fixed thereon a cylindrical collar adapted to fit the cylindrical end opening, and a circumferentially restricted shoulder adapted to engage the wall of the end opening longitudinally of the shell; said wall being notched to admit said shoulder, and means being provided for securing the terminal against rotation upon the shell. 105 110 115

4. In a fuse, the combination of a shell, an associated member having a flange portion with a notch therein, a terminal member having a shoulder portion, a member mounted on said terminal member and having a shoulder portion which is receivable by said notch, said shoulders and flange cooperating normally to prevent longitudinal movement of the terminal member, a disc fitted over said terminal member and having a projection receivable by said notch normally to prevent turning movement of the terminal member, and means for holding said disc in a locked position. 120 125 130

5. In a fuse, the combination of a shell, a

- member threaded into the end of said shell and having an inwardly extending flange with a notch therein, a terminal member having a shoulder, a member mounted on said terminal member and having a shoulder receivable by said notch, said shoulders and flange normally preventing longitudinal movement of said contact member, an apertured disc for receiving the contact member and having a projection receivable by said notch normally for preventing a turning movement of said terminal member, and an end cap for holding said disc in locked position.
- 15 6. In a fuse, the combination of a shell, a threaded member mounted in the end of the shell and having a flange with a notch therein and with a groove registering with said notch, a terminal member having means associated therewith including oppositely arranged shoulders, one of which is receivable by said notch, said shoulders and flange cooperating normally to prevent longitudinal movement of the terminal member, a disc fitted over said terminal member and having a projection receivable by said notch normally for preventing turning movement of said terminal member, said disc preventing gases passing radially inwardly toward contact member, and for directing such gases outwardly through said groove, and means normally for holding the disc in a locked position.
- 20 7. In a cartridge fuse, a shell, and a terminal blade constructed respectively with an internal and an external cylindrical por-
- tion, said cylindrical portions fitting the one around the other to provide a bearing which stabilizes the blade in all directions; said cylindrical portions being assembled by relative axial movement of the members; and said members having overlapping projections interengaged by rotation to interlock the parts against separation after their cylindrical portions have been brought into coincidence.
- 25 8. In a cartridge fuse, the combination of a shell having a cylindrical end opening, a terminal blade having a reduced neck leaving a shoulder on the blade which limits the introduction of the blade into the shell, a cylindrical collar fixed upon the reduced neck of the terminal and fitting the cylindrical end opening of the shell, and means for securing the terminal against withdrawal from the shell.
- 30 9. In a cartridge fuse, the combination of a shell and a terminal blade, provided the one with a notched flange and the other with shoulders adapted to pass through the notches of the flange and to engage therewith by partial relative rotation of the shell and blade, a shouldered member having a cylindrical bearing portion fitting within the flange and stabilizing the support of the terminal upon the shell, and a locking disk which fits the terminal blade and has a seat upon the shell to resist rotation of the blade to unlocking position.
- 35 Signed at Chicago, Illinois, this 29th day of August, 1918.

ALFRED L. EUSTICE.
